UNITED STATES PATENT OFFICE.

HOWARD M. BARBER, OF STONINGTON, CONNECTICUT, ASSIGNOR TO C. B. COTTRELL & SONS COMPANY, OF STONINGTON, CONNECTICUT, A CORPORATION OF DELAWARE.

SHEET-FEED GUIDE MECHANISM.

Application filed January 17, 1924. Serial No. 636,796.

To all whom it may concern:

Be it known that I, HOWARD M. BARBER, a citizen of the United States, and resident of Stonington, in the county of New London 5 and State of Connecticut, have invented a new and useful Improvement in Sheet-Fee Guide Mechanisms, of which the following is a specification.

In sheet feed guide mechanisms it has 10 heretofore been customary to provide each of the sheet stops with its own independent adjusting mechanism for bringing the sheet stops into proper register with their sheet taking devices, the operation being quite 15 tedious and difficult because of the inaccessible location of the sheet stop adjusting mechanisms and the difficulty in bringing the sheet stops into proper relationship with each other.

20 The object of my invention is to provide a simple, accessible and effective means for adjusting the sheet stops to bring them into proper register with the sheet taking device, such adjusting means extending to one 25 side of the machine and being operable to adjust either end of the sheet stop carrying rock shaft toward and away from the sheet taking device to bring the sheet stops into proper position with respect to said 30 sheet taking device.

A practical embodiment of my invention is represented in the accompanying drawings, in which—

Fig. 1 represents a sheet feed guide mechanism and its adjacent parts in side elevation.

Fig. 2 represents the same in top plan, the sheet taking rotary cylinder being removed.

Fig. 3 represents a detail section on a 40 larger scale taken in the plane of the line III—III of Fig. 2, looking in the direction of the arrows.

Fig. 4 represents a detail section on a 45 larger scale, taken in the plane of the line IV—IV of Fig. 2, looking in the direction of the arrows.

The sheet taking device may be a rotary cylinder 1, suitably mounted between side frames 2 and 3 of the machine. The cam 50 4 is carried by the shaft 5 of the rotary cylinder 1 for controlling the movement of the sheet stop shaft operating lever 6 of the sheet feed guide mechanism.

The sheet feed guide mechanism includes

the endless tape carrier 7, the upper and 55 lower sheet guides 8 and 9 and the sheet stops 10 carried by the rock shaft 11. Each end of the sheet stop rock shaft 11 is mounted in the head 12 of an end bearing, which head is slidably mounted and held against turning between upper and lower branches 13 and 14 of a yoke of a socket 15, secured fixedly to the side frame.

Each of these end bearings is provided 60 with a screw-threaded shank 16 which passes through a recess 17 in the socket 15. The shank 16 of one end bearing has a worm gear 18 threaded thereon and the shank 16 of the other end bearing has a worm gear 19 threaded thereon, both of said worm gears being 70 yieldingly held pressed against the ends of their sockets by coil springs 20 surrounding the shanks in the recess 17 of the sockets 15.

An inner cross shaft 21 is mounted in the 75 side frames 2 and 3 and it is provided with a worm 22 which meshes with the worm gear 18. An outer concentric cross shaft 23 is rotatably mounted on the inner cross shaft 21 and it is provided with a worm 24 which 80 meshes with the worm gear 19. At one side of the machine the end of the inner cross shaft 21 is provided with a handle 25 and the corresponding end of the outer cross shaft 23 with a handle 26. A set screw 27 85 is carried by the handle 26 in position to lock the two shafts to turn together when desired, to move the sheet stop carrying rock shaft bodily toward and away from the sheet taking device.

The rock lever 6 is fixed to the end of the sheet stop shaft 11 and a spring 28 is used for holding the stud or roller 29 at the free end of said lever against its controlling cam 4.

A suitable train of gears 30, 31, 32, 33, 34, 35, 36 drives the endless tape carrier 7, the shaft 5 of the cylinder 1 being provided with a gear 37 meshing with the gear 31 to rotate the cylinder.

The means for adjusting the position of the free end of the sheet stop shaft operating lever 6 comprises a short arm 38 on said lever and a lug 39 on the socket 15, through which lug an adjusting screw 40 passes into engagement with the short arm 38 of the lever 6.

In operation:

By loosening the set screw 27, either end of the sheet stop rock lever may be adjusted toward and away from the sheet taking device through the worm gear connections 22, 18 or 24, 19, by turning the handle 25 or handle 26, bringing the rock shaft into parallelism with the sheet taking device. The set screw may then be tightened to lock the shaft 23 to the shaft 21 when the turning of either handle will move the rock shaft bodily toward or away from the sheet taking device to bring the sheet stops into proper register therewith.

It will thus be seen that simple, accessible and effective manually operated means is provided at one side of the machine whereby either one or both cross shafts may be rotated to move the end bearings to bring the sheet stop rock shaft into parallelism and to move said rock shaft bodily to bring the sheet stops into proper register.

It is evident that various changes may be resorted to in the construction, form and arrangement of the several parts without departing from the spirit and scope of my invention; hence, I do not wish to limit myself to the particular embodiment herein shown and described, but

What I claim is:—

30 1. A sheet taking device and a sheet feed guide mechanism therefor comprising, a rock shaft, sheet stops carried thereby, and means for adjusting either one or both ends of the shaft to bring the shaft into parallelism and arranged to coact to bring the sheet stops into proper register with the sheet taking device.

40 2. A sheet taking device and a sheet feed guide mechanism therefor comprising, a rock shaft, sheet stops carried thereby, fixed sockets, end bearings for the rock shaft yieldingly mounted in said sockets, and means for adjusting either one or both ends of the shaft to bring the shaft into parallelism and arranged to coact to bring the sheet stops into proper register with the sheet taking device.

45 3. A sheet taking device and a sheet feed guide mechanism therefor comprising, a rock shaft, sheet stops carried thereby, fixed sockets, end bearings for the rock shaft yieldingly mounted in said sockets, and means for adjusting either one or both ends of the shaft to bring the shaft into parallelism and arranged to coact to bring the

sheet stops into proper register with the sheet taking device, said means comprising concentric manually operated cross shafts having worm gear connections with their respective end bearings.

4. A sheet taking device and a sheet feed guide mechanism therefor comprising, a rock shaft, sheet stops carried thereby, fixed sockets, end bearings for the rock shaft yieldingly mounted in said sockets, and means for adjusting either one or both ends of the shaft to bring the shaft into parallelism and arranged to coact to bring the sheet stops into proper register with the sheet taking device, said means comprising concentric manually operated cross shafts having worm gear connections with their respective end bearings, and means for locking the shafts to turn together.

5. A sheet taking device and a sheet feed guide mechanism therefor comprising, a rock shaft, sheet stops carried thereby, and means for adjusting either end of the shaft to bring it into parallelism with the sheet taking device and the sheet stops into proper register with the sheet taking device, said means comprising fixed sockets, end bearings for the shaft mounted in said sockets and provided with shanks, worm gears screw-threaded on said shanks, and concentric manually operated cross shafts having worms meshing with their respective worm gears.

6. A sheet taking device and a sheet feed guide mechanism therefor comprising, a rock shaft, sheet stops carried thereby, and means for adjusting either end of the shaft to bring it into parallelism with the sheet taking device and the sheet stops into proper register with the sheet taking device, said means comprising fixed sockets, end bearings for the shaft mounted in said sockets and provided with shanks, worm gears screw-threaded on said shanks, concentric manually operated cross shafts having worms meshing with their respective worm gears, operating handles for said cross shafts at the same side of the machine, and means for locking the two cross shafts to turn together.

In testimony, that I claim the foregoing as my invention, I have signed my name this fourteenth day of January A. D. 1924.

HOWARD M. BARBER.
